ROTARY HAND STAND MACHINE

Kiyoshi Totsuka, 43 Chokyuji-cho, Higashi-ku,
Nagoya, Japan

Filed Oct. 11, 1965, Ser. No. 87,385

Term of patent 14 years

(Cl. D34—5)

FIG. 1

FIG. 2

FIG. 3

FIG. 4

FIG. 1 is a front elevational view of a rotary hand stand machine showing my new design,

FIG. 2 is a plan view,

FIG. 3 is a left side elevational view, and

FIG. 4 is a right side elevational view of my new rotary hand stand machine.

I claim:

The ornamental design for a rotary hand stand machine, as shown.
